UNITED STATES PATENT OFFICE.

ANDREW LOUIS WEIS AND FRANK NICOLAUS WEIS, OF MONROE, MICHIGAN,
ASSIGNORS TO THE WEIS-VAN WORMER COMPANY, OF MONROE, MICHIGAN,
A CORPORATION OF MICHIGAN.

BOX-MAKING MACHINE.

1,095,536.

Specification of Letters Patent.

Patented May 5, 1914.

Application filed August 5, 1911. Serial No. 642,496.

To all whom it may concern:

Be it known that we, ANDREW L. WEIS and FRANK N. WEIS, citizens of the United States, residing at Monroe, in the county of Monroe and State of Michigan, have invented certain new and useful Improvements in Box-Making Machines; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to mechanism for performing one of the steps in the manufacture of boxes composed of paper, pastboard or the like. Assuming that the box is completed, except that the several overlapping flaps or members which compose one end of the box remain to be pasted or glued together and that the opposite end of the box is closed but has a hole therethrough for the reception of a stopper; the present invention is designed to press together the pasted or glued meeting surfaces of the flaps or members of the unfinished end and to hold them tightly pressed together for a time until the adhesion between such surfaces shall be complete.

To this end, our invention consists of the devices and arrangement of parts herein-after specified, and shown and illustrated in the accompanying drawings, in which—

Figure 1 is a front-elevation of our machine with certain portions omitted for the sake of clearness, as will hereinafter fully appear; Fig. 2, a top-plan view of the same with a portion of the top table broken away; Fig. 3, a side-elevation of the step-by-step turning mechanism hereinafter referred to; Fig. 4, a top-plan view taken on line 4—4 Fig. 1; Fig. 5, a side-elevation, partly in section, of the sectional table or bed and the platen hereinafter referred to with the means for actuating the same in operative position; Fig. 6, an enlarged view, in detail, of the sectional folding table, hereinafter referred to, in position to receive the box to be finished, together with the support therefor, and the device for lifting the box at the completion of the operation, and Fig. 7, a top-plan view of the same.

Corresponding parts are represented by like numerals throughout the drawings.

In the drawings, 1 is a pedestal upon the top of which is rotatively mounted a circular frame consisting of an upper ring 2 and a lower ring 3. These two rings are held in proper separated relation by bars 4 and have spokes and hubs and are supported upon the top of the pedestal and journaled upon shaft 5 which is supported in a socket in the top of the pedestal 1, the shaft being held against rotation by a set-screw 6. Rigidly secured to and projecting upwardly from the ring 3 is a series of posts or standards 7, each having a central vertical slot in its top, as at 7^a, (Figs. 5 and 6.)

8—8 are pairs of identical plates, each having a flat-surfaced member 8^a, rectangular in outline or otherwise,—according to the shape of the box to be operated upon,—and each having a finger 8^b formed integral therewith and projecting at a right angle to the member 8^a. The two plates are each pivoted, as at 8^c, at the meeting angle of the parts 8^a—8^b in the upper end of the slots 7^a of the bars 7. The arrangement of these pairs of plates and their pivots is such that when the members 8^a are thrown into upright position the flat surfaces of the two members meet and exactly coincide, and such that when the parts 8^a are swung outwardly away from each other with their flat surfaces in the same horizontal plane the two arms 8^b will meet, as shown in Fig. 5 and in dotted lines in Fig. 6, and will hold the parts 8^a so that their flat surfaces will now present a horizontal bed or table. The slot 7^a permits this tilting of the pairs of plates upon their pivots. Slight friction-springs or pieces 8^d (see Fig. 7.) are interposed between the jaws of the slots 7^a and the sides of the tilting members 8^a—8^b to prevent the parts 8^a from accidentally falling apart.

Each of the upright bars 7 is provided near its lower end with a plate 9 which is movable vertically upon the part 7. The normal height of these plates upon the standards 7 may be regulated to conform to the size of the box to be operated upon, by means of supporting pins 9^a inserted in holes 9^b, (Fig. 5.)

If the two members 8^a be brought together, as indicated in Figs. 6—7, and if the opening in box A, indicated in dotted lines

in Fig. 6, be slipped over the upturned edges of the parts 8^a, the margin of the opening in the box will strike the horizontal arms 8^b and the parts 8^a will fall asunder into 5 flat horizontal position, within the box, as indicated in Fig. 5, and the box will now rest with its lower end upon the plate 9. Now the flaps of the upper end of the box, having been suitably provided with a proper 10 adhesive, may be pressed inwardly and down upon the flat upper surface of the sectional table consisting of the parts 8^a. If these flaps be pressed with sufficient force and held closely together for a sufficient 15 time the work of closing and securing the uncompleted end of the box will be finished. This part of the operation is accomplished by means of the mechanism now to be described.

20 Upon the ring 2, at intervals corresponding with the standards 7, are pairs of upright lugs 10. Each of these pairs of lugs pivotally supports, as at 11, a frame 12 (see Fig. 5) resembling somewhat in side-elevation a bell-crank lever. The arms 12^a of this frame carry a roller 13 and the arms 12^b of the frame carry a roller 14. Passing through the arms 12^a are pins 15, headed at 25 their upper ends and rigidly connected at their lower ends with a platen 16 coinciding in outline with the flat surface of the table 8^a—8^b. A stiff spring 17 is interposed between the platen and the arms 12^a.

18 is a flat ring or wheel rigidly secured 30 to and concentric with the upper end of the fixed shaft 5. This ring is not continuous, but has, at the front part of the machine, a gap. (See Fig. 2.) In the gap is secured a curved bar 19, which is formed as a cam 20, upon which the rollers 13—14 successively 35 ride as the frame 2—3 is rotated. The cam 20 and rollers 14 serve to successively throw the arms 12^a, the rollers 13 and the platens 16 into upright position, as indicated by the 40 dotted lines in Fig. 5. At this point there is a pause in the rotation of the frame 2—3 to permit the box-blank under treatment to 45 be slipped into place over the standard 7. As the frame 2—3 starts forward on its 50 rotary course, the cam is of such contour that it releases the roller 14 and at the same time swings the roller 13 down, at 18^a, so that it passes under and rides upon the lower 55 side of the ring 18. This contact, through spring 17, presses the platen 16 downwardly with a heavy but yielding pressure, thus compressing the flaps of the box closely between the top of the table 8^a and the bottom of the platen. This pressure is con- 60 tinued during the greater part of the revolution of the frame 2—3 and during its several pauses until the roller 13 emerges from beneath the ring 18 at 18^b where the roller 13 and the platens are released to be by the 65 cam 20 again swung upwardly, as indicated

by the dotted lines in Fig. 5, as above described. In the accompanying drawings there are shown,—for illustration,—twelve holders and presser-mechanisms all like the one hereinbefore described, as will be readily understood, although the parts are not all repeated in the drawings. The step-by-step rotation of the frame 3 and its appendages may be performed by suitable power driven mechanism, but in the present instance is effected,—for illustration,—by means of a treadle 21 pivoted upon the base, as at 22, and pivotally connected by rod 23 with one arm of a bell-crank lever 24, the other end of this lever being loosely connected with a bar 25 sliding in a housing 26 and carrying a pawl 27 which engages the teeth of a ratchet-wheel 28 fastened concentrically to the underside of frame 2—3. The pawl is held against the ratchet by means of the pressure of a flat spring 29, one end of which is rigidly secured to the sliding bar 25. The treadle is held normally elevated by spring 21^a but when the treadle is depressed by the foot of the operator, the pawl,—through the sliding bar and bell-crank lever,—moves the ratchet-wheel and the frame 2—3 to which it is secured a single step which, in the present instance, is one-twelfth of a revolution. The frame now 95 pauses and the platen immediately in front of the operator at the same time is, by the cam 20, thrown upwardly and out of the way, as illustrated in dotted lines in Fig. 5, so that the completed box may be removed 100 and replaced by an uncompleted one.

To facilitate the removal of the box after it has emerged from beneath the ring 18 at 18^b we provide a radial arm 30 rigidly connected, as at 31, to the pedestal 1 and carrying at its outer end a vertically adjustable rod 32 which has at its top a wedge-like cam 33 which lies in the path of the beveled underside of the plates 9. As the boxes successively emerge from beneath the seg- 110 mental ring 18 and as the platen 16 is lifted out of the way, the plate 9 rides upwardly upon the inclined surface of the member 33 and lifts the box some distance so that it may now be readily removed from the ma- 115 chine, by a reversal of the above described movement of the parts 8^a—8^b. Above and supported by the ring 18 is a flat circular table-top 34 which protects the mechanism located below the table and serves as a convenient resting place for boxes as they are supplied to the operator and as they are removed from the machine.

Having described our invention, what we claim and desire to secure by Letters Pat- 125 ent is,—

1. In a device of the described character, a frame, a standard upon the frame, a sectional table pivoted upon the standard, the sections of such table being pivoted to be 130

thrown into parallel relation or into the same plane, combined with a platen co-acting with said table.

2. In a device of the described character, 5 a standard, a pair of plates pivotally connected to the upper end of the standard, the pivotal arrangement being such that the said plates may swing into parallel relation or into the same plane, upon each plate—at an 10 angle thereto—a finger, said fingers serving as means for tilting their plates from parallel relation into the same plane, combined with a platen corresponding to said plates when disposed in the same plane, and means 15 for actuating said platen.

3. In a device of the described character, a standard, a pair of plates pivotally connected to the upper end of the standard, the pivotal arrangement being such that the said 20 plates may swing into parallel relation or into the same plane, upon each plate—at an angle thereto—a finger, said fingers serving as means for tilting their plates from parallel relation into the same plane and serving 25 as stops which limit the movement of the plates upon their pivots, combined with a platen corresponding to said plates when disposed in the same plane, and means for actuating said platen.

30 4. In a device of the described character, a standard, a pair of plates pivotally connected to the upper end of the standard, the pivotal arrangement being such that the said plates may swing in parallel relation or into 35 the same plane, upon each plate—at an angle thereto—a finger, said fingers serving as means for tilting their plates from parallel relation into the same plane and serving as stops which limit the movement of the plates 40 upon their pivots, combined with a member (9) slidable upon said standard, and means for actuating said member.

5. In a device of the described character, a rotary frame, a series of standards carried 45 by said frame, tables supported by said standards, a series of platens corresponding to said tables, means for holding said platens and tables pressed in operative relation during part of the rotation of the table, means 50 for imparting to the frame a step-by-step rotation, means for successively separating the platens and the tables during the pause

between the steps of such rotation, plates movable longitudinally relatively to said standards, and means for actuating said 55 plates in harmony with the step-by-step movement of the frame.

6. In a device of the described character, a pedestal, a frame rotatively mounted upon the pedestal, means for imparting a step-by-step rotation to the frame, a fixed shaft concentric with the pedestal and the frame, a ring rigidly connected with the shaft, a series of tables mounted upon the frame, a series of platens co-acting with said tables, a 60 cam upon said fixed ring, and means controlled by said fixed ring and cam for actuating said platens.

7. In a device of the described character, a pedestal, a frame rotatively mounted upon 70 the pedestal, means for imparting a step-by-step rotation to the frame, a fixed shaft concentric with the pedestal and the frame, a ring rigidly connected with the shaft and having a roller-track, a series of tables 75 mounted upon the frame, a series of platens co-acting with said tables, a cam upon said fixed ring, tilting supports for said platens, rollers on said tilting supports which successively engage said cam to tilt the supports 80 and which then successively engage said roller-track to hold the platen, supports pressed toward their tables.

8. In a device of the described character, a fixed ring, a cam rigidly connected with 85 said ring, a frame rotatable in operative relation to said ring and cam, a series of platen-supports carried by said frame, platens carried by said supports, rollers mounted upon said platen-supports and arranged to successively engage said cam to lift the platens and to then roll upon said fixed ring to hold the platens in operative 90 position, combined with a series of tables carried by said frame and co-acting with 95 said several platens.

In testimony whereof we affix our signatures in presence of two witnesses.

ANDREW LOUIS WEIS.
FRANK NICOLAUS WEIS.
